UNITED STATES PATENT OFFICE.

GEORGE GEDDIS, OF DETROIT, MICHIGAN.

ENGINE.

Application filed November 8, 1922. Serial No. 599,655.

My invention relates to engines, and the object of my invention is to provide an engine having novel and improved structural features and a high efficiency in operation.

A further object of the invention is to provide an engine which is capable of numerous and varied applications in which the working conditions are widely varied.

10 In the attached drawings:

Figure 1, illustrates in side elevation an engine made in accordance with my invention;

Fig. 2, is an end elevation;

15 Fig. 3, is a section through the engine taken on the line 3—3, Fig. 2;

Fig. 4, is a section on the line 4—4, Fig. 1, and

20 Fig. 5, is a horizontal section of the engine on the line 5—5, Fig. 2, illustrating the details of the valve mechanism.

With reference to the drawings, my engine comprises in one form a motor casing 1 which in the present instance is connected by 25 arms 2 with a pump casing 3, the casings 1 and 3 being supported respectively on pedestals 4 and 5 constituting in the present instance a part of the casings. The arms 2, 2, in the present instance are secured at opposite ends to the casing 1 and the casing 3 by means of bolts or studs 2a.

With reference to Figs. 2, 3, 4 and 5, of the drawings, the motor casing 1 comprises a cylinder casting 45, including a main cylinder 46, and at the top thereof two valve chambers or cylinders 47 and 48, the axes of all the cylinders in the present instance being parallel, the cylinders 47 and 48 being in the same horizontal plane and the main cylinder 46 directly underlying the cylinders 47 and 48. The main cylinder 46 is closed at its opposite ends by cylinder heads 49 and 50, while the opposite ends of each of the cylinders 47 and 48 are closed in the present instance by means of threaded caps 51, 51, which screw into threaded counterbores at the ends of the cylinders.

Each of the cylinders 47 and 48 communicates through a port, respectively 52 and 53, with a central steam port or chest 54, from which extends a port 55, through which the port 54 may be connected to a source of live steam, the port 55, as shown in Figs. 2, 3 and 4, extending in the present instance through the top of the casing 45.

As best illustrated in Fig. 5, the ports 52

and 53 are at opposite ends of the steam chamber 54, while the port 55 enters the chamber 54 at the center thereof. In the bottom of each of the cylinders 47 and 48 and at the centers thereof is a port, respectively 56 and 57, which ports communicate through a common passage 58 with a port 59 in the side of the casing, these ports 56 and 57 constituting exhaust ports, as will be described hereinafter. From each of the cylinders 47 and 48 and from a point in each close to that end of the cylinders into which open the ports 52 and 53, is a passage 61 and 62 respectively, which extends into the main cylinder 46, these passages entering the said main cylinder at opposite ends thereof and constituting means for the passage of steam to and from the said main cylinder.

As best shown in Fig. 5, each of the cylinders 47 and 48 has in its ported end a bushing 63 which reduces the diameter of the cylinder at that end and in which operate the small ends 64 and 65 of the double pistons 66 and 67 which respectively occupy the said cylinders 47 and 48, the said double pistons also comprising large ends 68 and 69 in each case joined to its companion small end by a connecting rod 70. Also as best shown in Fig. 5, the ports from which extend the passages 61 and 62 are formed in the said bushings 63, the smaller ends 64 and 65 of the pistons 66 and 67 thereby constituting valves which control the said passages.

From the large end of each of the cylinders 47 and 48 extends a small passage 72 and 73 respectively in valve chambers 74 and 75 formed respectively in the cylinder heads 49 and 50, each of the valve chambers 74 and 75 communicating with the main cylinder 46. Slidably mounted in each of the chambers 74 and 75 is a pilot valve 76 and 77 respectively, each of which comprises a hollow stem 78 normally projecting from the cylinder head 49 which it occupies into the cylinder 46. The projecting ends of the stems 78, 78, are open, and each of the stems is provided with a series of openings 79 and 80 respectively, through which communication is established between the interior of the hollow stems 78, 78 and the chambers 74 and 75. Each of the said chambers 74 and 75 also communicates by means of passages 81 and 82 with opposite ends of the steam chamber 54, and the valves 76 and 77 are such that when seated these latter chambers 81 and 82 are shut off both

from the passages 74 and 75, and from the interior of the hollow stems 78 of the respective valves. When, however, the valves 76 and 77 are forced from their seats, the chambers 81 and 82 are in communication respectively with the passages 74 and 75. Each of the valves 76 and 77 also comprises an extension 83 which is established in a recess 84 in the respective cylinder heads 49 and 50, there being confined between the end of the extension 83 and the bottom of the recess 84 a spring 85 which tends to retain the valves on their respective seats. In the present instance, the recess 84 is formed in a plug 86 which is threaded into the respective cylinder heads 49 and 50, removal of these plugs permitting withdrawal from the chambers 74 and 75 of the entire valve structure 76-77.

Within the cylinder 46 is a piston 87 which in the present instance is connected with the piston rod 10 which also carries the piston 11 which operates in the cylinder 6, and it will be noted, as illustrated in Fig. 3, that when the piston 87 is at either end of its stroke, it has engaged the inner projecting end of the stems 78, 78, of either one or other of the valves 76 and 77, and has forced the valve from its seat. Also as best shown in Fig. 3, the cylinder head 50 comprises a stuffing box 88 through which the connecting rod 10 passes.

The operation of the aforescribed mechanism is as follows: As previously stated, steam is admitted to the casing 45 through the port 55, the steam first entering the chamber 54. From this chamber the steam at all times has access through the passages 81 and 82 to the valve chambers 74 and 75, so that when as illustrated in Fig. 3, the piston has reached one end of its stroke and has thereby removed one or other of the operating valves 76 and 77 from its seat, steam is admitted into one or other of the passages 74 and 75, through which it passes to the end of the associated cylinders 47 and 48. In the present instance, the piston 87 has reached the outer end of its stroke and has forced the valve 76 from its seat whereby steam is admitted through the passages 81 and 72 to the cylinder 48 in back of the large piston 69, the steam tending to force the piston 57 to the right and into the position in which it is shown in Fig. 5. Although the small end of the cylinder 48 is continuously open to the live steam in the chamber 54 through the port 53, the difference in the area of the piston ends 69 and 65 permits the steam entering the cylinder through the port 72 to move the piston into the position shown in Fig. 5. The first part of this movement of the piston 67 cuts off the port 62 and breaks communication between the steam chamber 54 and the right hand end 70 of the cylinder 46, as shown in Fig. 5, while

the final movement of the piston 67 into the position shown in Fig. 5 connects the port 62 with the exhaust port 57, and throws the right hand end of the cylinder 46 open to the exhaust.

Immediately following the opening of this portion of the cylinder 46 to the exhaust, steam in the chamber 54 operates against the small end 64 of the piston 66 which occupies the cylinder 47 and forces it over to the position shown in Fig. 5, this movement of the piston 66 by the steam which enters the cylinder 47 through the port 52 being permitted by the fact that the large end of the cylinder 47 has been thrust open to the exhaust through the passage 73 which communicates through the openings 80 in the valve 77 and the hollow stem 78 with the right hand end of the cylinder 46 as shown in Fig. 3, this end of the cylinder 46 having been, as previously described, connected with the exhaust.

The initial movement of the piston 66 to the right and into the position shown in Fig. 5 first closes the port 61 and disconnects this port from the exhaust port 56, thereby shutting off the left end of the cylinder 46, as shown in Fig. 3 from exhaust, the final movement of the piston 66 throwing open the port 61 to the steam which enters the cylinder 47 from the chamber 54, and thereby allowing the live steam to pass into the left end of the cylinder 46 behind the piston 87, this piston accordingly being forced to the right and in the direction of the arrow shown in Fig. 3. The initial movement of the piston 87 permits the closing of the valve 76 by the spring 85, thereby disconnecting the large end of the cylinder 48 from the steam chamber 54, but steam is still permitted to enter the large end of the cylinder 48 through the hollow spindle 78 of the valve 76, the openings 79 in said hollow spindle, and the passage 72, the pressure in the large end of the cylinder 48 thus being maintained and retaining the valve 67 in the position shown in Fig. 5. Until, therefore, the piston 87 approaches the end of its stroke to the right, the pistons 66 and 67 remain as shown in Fig. 5. As the piston 87 however, reaches the end of its stroke, it engages the projecting end of the stem 78 of the valve 77, forcing the latter from its seat and permitting steam to pass from the chamber 54 through the passages 82 and 73 to the cylinder 47 in back of the large end 68 of the piston 66, this having the effect of forcing this piston from the position which it occupies in Fig. 5 to the left, first shutting off the port 61 from the chamber 54, and finally connecting the port 61 with the exhaust.

Connection of the port 61 with the exhaust has the effect of permitting the steam operating against the small end 65 of the piston 67 to force this piston to the left, connecting

the right hand end, as shown in Fig. 3, of the piston with the steam chamber 54, and driving the piston 87 to the left, thus completing the cycle.

5 It will be noted that when the piston engages the end of the stem 78 of either of the valves, it has the effect of closing the open projecting end and thereby prevents any escape of steam from the chamber 54 to the 10 exhaust within the cylinder 46.

In operation, the unit has been found to have an extremely quick valve action, the delay at the ends of the stroke of the piston 87 being reduced to a minimum, and there 15 being maintained as a consequence a substantially constant pressure on the pump.

When the engine is employed for pumping compressed air and particularly at high pressure, I have found that there is, with 20 the hereinbefore described machine, a tendency for the piston valves 66 and 67 to rebound at the end of their strokes. Therefore, in order to prevent such rebounding of the valves 66 and 67 and to provide a smooth 25 working machine, I employ two additional small ports 90 and 91 connecting the chambers 47 and 48 when the engine is used for pumping air. The ports 90 and 91, as best shown in Figs. 2, 4 and 5, are formed in 30 the portion of the casing over the chamber 54 and communicate at the top of the casing with tapped holes 92 and 93. The ports 90 and 91 are disposed adjacent to each end of the chambers 47 and 48 so that when the 35 valves 66 and 67 are at each end of their strokes passages will be provided between the two chambers. The holes 92 and 93 have mounted therein screw studs 94 and 95, which constitute valves capable of completely 40 closing the ports 90 and 91, and for opening them to any desired degree. Lock nuts 96 and 97 are provided on the studs to retain them in any position desired. The ports 90 and 91 supplement the normally active 45 ports in the ends of the valve chambers 47 and 48 hereinbefore described, and thus afford a much quicker and more accurate movement of the valves with a general increase in the efficiency of the entire machine. It will, of course, be understood that 50 by means of the studs 94 and 95, the ports 90 and 91 may be opened to any desired extent, or may be completely closed as desired, such adjustment being easily effected 55 while the machine is operating.

It is possible to reduce the speed of the motor mechanism to an exceedingly low point while still maintaining a practically constant pressure on the pump. The mechanism further has many structural advantages not commonly found in mechanism of this nature, particularly in the facilities for disassembling the parts for repair or for replacement of worn or damaged parts. It 60 will be noted, for example, that by re-

moval of the plugs 51 at the ends of the cylinders 47 and 48, the pistons and the sleeve 63 may be removed from the casing without difficulty and without otherwise interfering with the mechanism, this same provision for quick disassembling being made, as previously described, in the case of the valves 76 and 77. The same advantages are found, as previously described, in the pump end of the engine. 75

It will be understood that the invention is not to be confined to the details illustrated in the drawings, since considerable modification is possible with no departure from the essential features of the invention. 80

I claim:

1. The combination with a main cylinder, of a piston mounted in said cylinder, a port at each end of the cylinder, a pair of independent valve chambers connected respectively with said ports, passages establishing communication between the opposite ends of the main cylinder and the respective valve chambers, and pilot valves controlling said passages and normally projecting into the 85 cylinder. 90

2. The combination with a main cylinder, of a piston mounted in said cylinder, a port at each end of the cylinder, a pair of independent valve chambers respectively connected with said ports, a steam chest communicating with each of said valve chambers, a valve in each of said chambers, a chamber at each end of the cylinder and communicating therewith, passages establishing communication between the respective valve chambers and the chambers at the opposite ends of the cylinder, a passage extending from each of the latter chambers to the steam chest, and pilot valves in said chambers normally projecting into the main cylinder and controlling the connection between the aforesaid passages and between the passages and the cylinder. 95 100

3. The combination with a main cylinder, of a piston in said cylinder, a port at each end of the cylinder, an independent valve chamber communicating with each of said ports, a steam chest communicating with both of said valve chambers, a piston valve in each of said chambers comprising each a pair of connecting pistons of different diameters, exhaust ports in each of said valve chambers, passages establishing communication between the main cylinder and each of said valve chambers, and pilot valves actuated by the piston and controlling said passages. 110 115

4. The combination with a main cylinder, of a piston mounted in said cylinder, a port at each end of the cylinder, a pair of independent valve chambers connected respectively with said ports, passages establishing communication between the opposite ends of the main cylinder and the respective valve 120 125 130

chambers, pilot valves controlling said passages and operatively associated with the pistons, and a pair of ports connecting the corresponding ends of the valve chambers.

5. The combination with a main cylinder, of a piston mounted in said cylinder, a port at each end of the cylinder, a pair of independent valve chambers connected respectively with said ports, passages establishing

communication between the opposite ends ¹⁰ of the main cylinder and the respective valve chambers, pilot valves controlling said passages and operatively associated with the pistons, a pair of ports connecting the corresponding ends of the valve chambers, and ¹⁵ adjustable valve means controlling said latter ports.

GEORGE GEDDIS.
